SEPARABLE CONNECTER

Harry E. Walker, Fairfield, Maine

Application October 6, 1933, Serial No. 692,420

2 Claims. (Cl. 284—18)

This invention relates to conduits composed of separable members or sections, and particularly to conduits used with motor vehicles to supply parts of such vehicles with conditioning means such as oil, grease, etc., although the invention may be otherwise used.

The connector embodying the present invention is an improvement on that disclosed by my Patent No. 1,885,657, and includes a freely movable delivering conduit member and a nipple-like receiving conduit member adapted to be fixed to a motor vehicle element requiring conditioning.

The chief object of the improved connector is to enable the delivering member to be operatively engaged in either of a plurality of different positions with the receiving member, so that when the location of the receiving member is such that the delivering member cannot conveniently be engaged therewith when moved in one direction, the engagement may conveniently be effected by moving the delivering member in a different direction.

Other objects will hereinafter appear.

Of the accompanying drawing forming a part of this specification,—

Figure 1 shows in perspective the delivering and receiving members of my improved connector separated from each other.

Figure 2 is a longitudinal section showing the delivering and receiving members operatively interengaged.

Figures 3 and 4 are side views showing the delivering member interengaged in different positions with the receiving member.

Figure 5 is a fragmentary edge view showing a portion of the delivering member.

Figure 6 is a section on line 6—6 of Figure 5.

Figure 7 is a section on line 7—7 of Figure 2.

Figure 8 is a longitudinal sectional view of the receiving member.

Figure 9 is a section on line 9—9 of Figure 8.

Figure 10 shows in perspective the leaf spring and valve shown by Figures 2 and 8.

Figure 11 shows the leaf spring in section, and provided with an integral valve.

Figures 12 and 13 are views similar to Figure 8, showing differently formed springs.

Figure 14 shows in section the body portion of the delivering member, and parts associated therewith.

The same reference characters indicate the same parts in all of the figures.

15 denotes the receiving conduit member which is preferably a nipple having an external

screw thread 16 whereby it may be fixed to a motor element, a longitudinal bore 17, and a flat side face 18 in which is formed an orifice 19 which constitutes the inlet of the member, and communicates with the bore thereof.

The connector includes a delivering member which is adapted to be coupled to a flexible supply pipe or hose 20, and includes a body portion 21 having end extensions 22 and 23 provided with spaced apart opposed inner faces.

The extension 22 is provided with an orifice 24 constituting the outlet of the delivering member, said orifice being preferably formed in a flexible diaphragm 30 constituting a part of the inner face of said extension, and functioning as presently described.

The opposed inner faces of the extensions 22 and 23 are formed to cooperate with external faces of the receiving member 15 to guide the delivering member in either of a plurality of paths on the receiving member and cause registration of the outlet 24, and the inlet 19 with each other when the delivering member is guided in either path.

In the embodiment here shown the extension 22 is provided with a flat inner face 27 (Figure 5), and the extension 23 is provided, as best shown by Figure 6, with two aligned reentrant or concave grooves, or guiding faces 28 and 29, said guiding faces intersecting each other at a point opposite the outlet 24, the face 28 extending at right angles to the face 29. The receiving member 15 is cut away to provide the flat face 18 which interrupts the cylinder surface of the member and extends to a stop shoulder 35. When the members are interengaged in alignment with each other, as shown by Figure 2, the flat face 18 bears on the flat face 27, the cylindrical surface of the receiving member bears on the guiding face 28, and the outlet 24 and inlet 19 register with each other, rotation of the delivering member on the receiving member being prevented by the flat faces 18 and 27.

When the members are interengaged at right angles with each other, either as shown by Figure 3, or by Figure 4, the flat face 18 bears on the flat face 27, the cylindrical surface of the receiving member bears on the guiding face 29, the outlet 24 and inlet 19 registering with each other.

The arrangement is such that the delivering member may stand either in a position in alignment with the receiving member, or in either of two positions at right angles therewith, when the members are operatively interengaged, so

that an operator may variously connect said members as required by the location of the receiving member, three positions of the delivering member relative to the receiving member being permitted, as shown by Figures 2, 3 and 4.

The end extension 22 is provided with three stop shoulders 22^a (Figures 1 and 4), against either of which the stop shoulder 15^a of the receiving member abuts when the members are operatively interengaged, the several shoulders 15^a and 22^a constituting stop means for locating the outlet 24 of the delivering member in alignment with the inlet 19 of the receiving member when said members are operatively interengaged.

It is obvious that the guiding faces 28 and 29 may be of other than concave form, the co-operating surface of the receiving member having a form complementary to that of said guiding faces.

I provide means for forming a grease tight joint surrounding the outlet 24 of the delivering member, and the inlet 19 of the receiving member, said means being preferably embodied in a flexible diaphragm 30, shown separately by Figure 14.

The delivering member is provided with clamping means formed to admit grease to the diaphragm and secure the margin thereof in position to cause the diaphragm to maintain a grease tight joint which surrounds the outlet of the delivering member and the inlet of the receiving member when said members are operatively interengaged, the diaphragm being forced against the flat surface 18 of the receiving member by the grease pressure, aided if desired, by a spring 31.

The means for securing the diaphragm and admitting grease thereto may be embodied as next described.

In the delivering member extension 22 is formed an internally threaded open mouthed cavity 32. The margin of the diaphragm bears on an annular seat 33 surrounding the cavity mouth. With the cavity 32 is engaged an externally threaded recessed plug 34 formed at one end to clamp the diaphragm margin against the seat 33, and admit grease to the diaphragm, the plug having grease passages 35. The plug recess is preferably formed to receive a spring 31 which exerts pressure on the diaphragm, addition to that caused by the grease.

The body portion 21 of the delivering member may have any suitable means for conducting grease to the passages 35 of the plug 34, and any suitable coupling means for engagement with the flexible supply conduit 20.

As shown by Figure 2, the body portion 21 has an enlarged bore portion 36, a screw threaded gland 37 engaged with said bore portion, and a tubular coupling nipple 38 adapted to rotate in the gland, and having at its inner end an annular shoulder 39 confined by the gland, and at its outer end a screw thread engaged with a fitting 40 in the conduit 20.

The coupling nipple and gland constitute a swivel connection between the conduit 20 and body portion 21, permitting the body portion to be turned on the coupling nipple and engaged in different positions with the receiving member 15 without twisting the flexible conduit member.

The shoulder 39 has a packing member 43 which is pressed by a spring 44 against the gland

37. A duct 45 extends between the chamber 36 and the plug passages 35.

It is preferable in many cases for lightness and compactness to reduce the cross sectional area of the delivering and receiving members to a minimum. It is also preferable to provide the receiving member 15 with a valve normally held by a spring, in position to close the inlet 19, the valve yielding to the pressure of grease forced into the inlet.

The desired reduction of the cross sectional area of the receiving member is permitted by the employment of a leaf spring, instead of the helical spring usually employed to yieldingly close a valve.

Figures 2, 8, 9 and 10 show a sheet metal leaf spring 42 formed to extend lengthwise of the bore 17 of the receiving member. One end portion of the spring is fixed in an end portion of the bore 17, preferably by confining its edges in slots 43, as is indicated by Figure 7. The opposite end of the spring carries a valve which is caused by the tension of the spring to close the inlet 19. The valve designated by 54, in Figures 8 and 9, is formed separately and engaged with an orifice in the free end of the spring 42. The valve may be a boss 55 integral with the leaf spring as shown by Figure 11. It will be seen that the form of the leaf spring is such that it does not objectionably obstruct the bore 17, grease being adapted to flow freely through the bore along the flat sides and thin edges of the spring. The spring shown by Figure 12 includes an end portion 46 having flat sides and a shank portion 47 connected by a neck portion 48 with the end portion 46, said shank and neck portions being attenuated and wire-like so that they do not objectionably obstruct the bore. One end of the shank portion is bent to form a tongue 49 which may be secured by solder, or otherwise, in an orifice 50 in the receiving member. The valve may be a boss 55, if desired.

The spring shown by Figure 13 includes a bent end portion 51 having flat sides, and a shank portion 52 secured to the receiving member by a fastener 53. The valve may be a boss 55.

It will be seen that the leaf spring occupies such a small portion of the cross section of the bore 17 that the cross sectional area of the receiving member 15 and the width of the space between the extensions 22 and 23 may be desirably reduced.

I claim:

1. A separable connector comprising a delivering conduit member having two spaced apart end extensions, one provided with a flat face containing the outlet of said member, and the other provided with two reentrant guiding faces extending at right angles with each other and intersecting each other at a point opposite said outlet, and a receiving conduit member having a flat face complementary to the flat face of the outlet-containing extension and containing the inlet of the receiving conduit, and a salient face complementary to either of said reentrant guiding faces, said delivering conduit member projecting from one end of the delivering conduit member in alignment therewith when one of said reentrant faces is engaged with the said salient face, and being adapted, when its other reentrant face is engaged with the salient face to project laterally from either side of the receiving conduit member so that the delivering member may stand in alignment with the re-

ceiving member or may project laterally from either side thereof, and therefore occupy either of three operative positions relative to the receiving member, stop means being provided for 5 locating the said members with the outlet of the delivering member coinciding with the inlet of the receiving member when said members are operatively interengaged.

2. A separable connector comprising a tubular 10 delivering conduit member having two spaced apart end extensions, one provided with a flat face containing the outlet of said member, and the other provided with two concave grooves extending at right angles with each other and 15 intersecting each other at a point opposite said outlet, said grooves constituting reentrant guiding faces, and a cylindrical receiving conduit member cut away at one side to form a flat face complementary to the flat face of the outlet-containing extension and containing the inlet 20 of the receiving conduit, and a salient face formed by a portion of the periphery of the receiving member and complementary to either of

said reentrant guiding faces, said delivering conduit member, when engaged with one of said guiding faces, projecting from one end of the receiving conduit member in alignment therewith, and being adapted, when engaged with the other guiding face, to project laterally from either side of the receiving conduit member, the arrangement being such that the delivering member may stand in alignment with the receiving member, or may project laterally from 10 either side thereof, and therefore occupy either of three operative positions relative to the receiving member, the extension having the outlet of the delivering member being provided with three stop shoulders, and the receiving member 15 with a single stop shoulder adapted to abut either of said three stop shoulders, the several shoulders constituting stop means for locating the outlet of the delivering member in alignment with the inlet of the receiving member 20 when said members are operatively interengaged in either of said three operative positions.

HARRY E. WALKER.
